INTERNAL-COMBUSTION ENGINE.

Application filed September 27, 1924. Serial No. 740,208.

My improvement relates to engines of the two cycle type, and particularly to means for controlling the admission of the combustible mixture and the expulsion of the products of combustion.

As hereinafter described; my invention includes the combination with an outer cylinder casing, having water jacket recesses cast in its inner walls, said recesses being primarily open inwardly of stationary cylindrical sleeves forming the inner walls of said jacket recesses; rotary tubular valves mounted to turn in said sleeves to vary the effective area of ports in the latter; said sleeves and valves being of larger diameters at their ends near the crank shaft; and pistons mounted to reciprocate in said valves; the larger diameters of the pistons cooperating with the larger diameters of the valves to form charging pump chambers between them to alternately intake and charge the combustible mixture into the combustion, power, chambers, which are in the smaller diametrical portions of said valves.

My invention also includes the various novel features of construction and arrangement hereinafter more definitely specified.

In said drawings; Fig. I is a longitudinal sectional view through the axes of the cylinders of a two cylinder, two cycle engine embodying my invention.

Fig. II is a transverse sectional view, taken on the line II, II in Fig. I, and through the axis of one of said cylinders and at right angles to Fig. I.

Fig. III is a transverse sectional view, taken on the line III, III in Fig. I, at right angles to the axis of said cylinders.

Fig. IV is a transverse sectional view, taken on the line IV, IV in Fig. I, at right angles to the axis of said cylinders.

Fig. V is a transverse sectional view, taken on the line V, V in Fig. I, at right angles to the axis of said cylinders.

Fig. VI is a diagram indicating steps in the operation of the power cylinder of said engine.

Fig. VII is a diagram indicating steps in the operation of the charging cylinder of said engine.

Fig. VIII is a longitudinal side elevation of a four cylinder, two cycle, engine embodying my invention.

Fig. IX is a transverse sectional view, taken on the line IX, IX in Fig. VIII, at right angles to the axis of the engine cylinders.

Fig. X is a fragmentary transverse sectional view, taken on the line X, parallel with the axes of the cylinders in Fig. VIII.

Fig. XI is a diagram indicating the steps in the operation of the engine shown in Figs. VIII to X inclusive.

Referring to the form of my invention shown in Figs. 1 to 7 inclusive; the cylinder casing 1, is conveniently formed as a single casting having water jacket recesses 2, primarily open at their inner sides and respectively surrounding the cylindrical bores 3, of which there are two in said casing. Said casing 1 is enlarged at the inner ends of said jacket recesses 2, to form the admission chamber 5, having the intake port 6, as shown in Figs. II and III. As shown in Fig. III; said admission chamber 5 also has a series of valve ports 7, opening inwardly through the annular reinforcing web 8, intermediate of the length of said chamber. Said casing 1 is also enlarged, near its outer end, to form the exhaust chamber 9 which, as shown in Figs. II and IV, has the outlet port 10. Said exhaust chamber 9 also has, between said water jacket recesses 2, circular series of exhaust valve ports 11, opening inwardly around the respective cylindrical bores 3.

As best shown in Figs. I and II; said cylindrical bores 3 are of smaller diameter at their outer ends than at their inner ends, and the ports 7 are presented in a conical zone intermediate of the larger and smaller diameters of said bores. As shown in Figs. I and II; each of said bores 3 is lined with a, primarily separate, stationary sleeve 13 having cylindrical portions of different diameters connected by a conical zone, fitted to said bores; said sleeves being fitted to said casing 1 in water tight relation therewith, so as to form the inner walls of the water jacket recesses 2 aforesaid. Each of said sleeves 13 has in its conical zone a circular series of admission ports 14, registering with said ports 7 and opening inwardly from the admission chamber 5, as shown in Figs. I and II. Said sleeves each have a circular series of ports 15 opening inwardly from

said admission chamber 5 through the smaller cylindrical portions of said sleeves, as shown in Figs. I, II and III. Each of said sleeves 13 also has a circular series of ports 16 registering with the ports 11 and opening into said exhaust chamber 9, as shown in Fig. IV.

As shown in Figs. I and II; rotary tubular valves 17 are respectively fitted to turn 10 within said stationary sleeves 13 and, as shown in Fig. III, said valve each have three circular series of ports 18, 19 and 21 corresponding, in spacing, with said ports 14, 15 and 16 and adapted to be presented in or out 15 of registry therewith, in accordance with the rotary position of said valves. Said ports 18 are in the conical zones, between the two cylindrical portions of each valve and said ports 19 and 21 are in cylindrical zones of 20 the same, smaller, cylindrical portion of each valve. However, said ports 21 do not open directly into the space within said valves, because each of the cylinders of the engine is provided with a stationary head 23, arranged 25 to be detachably bolted to said casing 1, and having a cylindrical portion 24 extending into the respective valves 17 and having a circular series of ports 25 registering with said ports 16 in the sleeves 13, as shown 30 in Fig. IV. As shown in Figs. I, II and III; I find it convenient to form the outer ends of said ports 25 in said heads 23 by sectoral bands 27 having thin edges at the circumferential margins of said ports 35 25 and so shaped that they press outwardly against the inner walls of said rotary valves 17 so as to tightly fit the latter, and prevent leakage to the exhaust chamber 9, from the piston chambers 28 in said valves which are 40 closed by said heads. I find it convenient to also provide each of said heads 23 with sealing rings 30 which are fitted in grooves therein and resiliently bear against the inner faces of said valves 17. I also find it convenient to form each of said heads 23 as a single hollow casting with a water chamber 31 therein, surrounding a central core 32 in which I mount an ignition plug 34. Said plugs 34 are, of course, suitably connected 45 in the ignition circuit of the engine and the water chambers 31 are also provided with suitable piping connections, in communication with the jacket recesses 2 and including means for circulating the water therein.

50 The lower edge of said cylinder casing 1 is rigidly connected with the crank housing 35 having three bearings 36 for the crank shaft 37, which has two cranks 38 extending radially oppositely from said shaft 37. As 55 shown in Figs. I and II; said cranks 38 are respectively connected with rods 39 engaging the wrist pins 41 in the respective pistons 42. Said pistons 42 each have portions of two different diameters fitted to reciprocate

in said valves 17; the outer smaller diameters 65 thereof being provided with resilient sealing rings 43, and the inner larger diameters thereof having similar sealing rings 45. The construction and arrangement is such that said pistons 42 cooperate with said valves 17 to 70 form between them charging pump chambers 46, as indicated in Fig. I, to alternately intake fresh fluid from said admission chamber 5, and discharge the same through the piston chambers 28, to drive out of the latter, 75 through said exhaust ports 25, 21, and 16, the products of combustion. That is to say, the peculiar construction and arrangement of valves and ports above described automatically effects what is termed "scavenging" 80 operation, insuring the thorough elimination of all products of combustion during each cycle of operation of the engine.

The various ports above described are arranged to be automatically opened and closed 85 at the proper times, by the continuous rotation of said valves 17. The means for effecting such rotation, as indicated in Fig. I, include the miter gear 48, which is rigidly connected with said crank shaft 37 and engaged with the miter gear 49 on the counter-shaft 50 which is journaled in the bearing 51 which is rigidly connected with said casing 1. Said countershaft 51 drives the pinion 52 which engages the gear 53 on the adjacent 90 valve 17, which gear is in mesh with a similar gear 53 on the other valve 17. I find it convenient to reduce the friction of rotation of said valves by providing each of them with two slip rings, 55 and 56, respectively 100 upon axially opposite sides of their gears 53. Said rings 55 bear against the inner ends of the sleeves 13, and said rings 56 bear against the outer surfaces of the sectoral abutment bearing blocks 57 which, as shown 105 in Figs. II and V, are supported by stepped flanges 58 in said cylinder casing 1. As shown in Fig. V; said bearing blocks 57 are respectively held by pairs of cap screws 59 and are of such length that they may be inserted and removed through the gaps 61 and 62 at the opposite ends of said casing 1; thus facilitating the assembling and disassembling of said valves 17 with respect to their seats in the engine. 115

Each of the cylinders in said engine operates alternately as a power cylinder and as a charging cylinder. In the form above described; a ratio of four to one has been chosen and each cylinder has four exhaust 120 ports 25, etc., reaching from the outer ends of the combustion chambers 28 inward far enough to insure proper opening area. The width of said ports 25 depends upon the relative opening and closing points of the exhaust ports 21 in said valves 17. The charge admission ports 15 are of double the number of said exhaust ports and the length of

such admission ports is determined by the outer limits of the pistons 42. The width of said admission ports may be larger than that of the exhaust ports but is limited by the necessity for safe closing of the admission ports, by the valves, before the pistons uncover them, as said admission ports are uncovered twice by the valves during one revolution of the engine, but only once, at the proper time, by the pistons. The inlet ports are, of course, opened when the pistons start inward, but are closed when the pistons reach dead center inward, and the discharge ports are opened at the beginning of the outward stroke of the pistons, as soon as the pressures in the charging chambers 46 and in the admission or receiving chamber 5 are equal, and said discharge ports close when the pistons reach the dead center outward.

In Fig. VI; the steps in the operation as a power cylinder are indicated. The arrow in said figure indicates the direction of rotation of said crank shaft 37. In said figure, 65 indicates the point where the exhaust opens, 66 indicates the point where the exhaust closes; and 67 indicates the location of the piston for those two points. The charge admission ports 68 open at the point 68 and are closed, by the piston, at the point 69, immediately preceding said exhaust closing point 66. Although the charge admission ports begin to register with each other at the point 70 and are fully registered at the point 71 so that they are wide open, as far as the valves 17 are concerned, they do not then admit the charge because they remain covered by the pistons. The length of the ports is determined with reference to the radial distance between the points 67 and 72 in Fig. VI.

In Fig. VII; the steps in the operation as a charging cylinder are indicated. The arrow in said figure indicates the direction of rotation of said crank shaft 37. The inlet ports start to open at the point 74 and close at the point 75. The discharge ports open at the point 76 and close at the point 78.

It may be observed, with reference to Figs. I and II, that when the cranks 38 are on opposite dead centers, the larger portion of the piston 42 at the left of Fig. I, acting as a charging pump has driven, from its charging chamber 46, a volume of fluid, at least equal to the capacity of the power chamber 28, into the latter, through the ports 15 and through said power chamber 28 to expel from the latter, through the ports 25, all of the products of combustion. At the same time, the piston 42 at the right of Fig. I has drawn into its charging chamber 46, a corresponding volume of fluid from said admission chamber or fluid receiver 5; ready to charge the same into and through the power chamber 28 of the other cylinder, in due time, in the cycle of operation.

The construction and arrangement above described has the following advantages:

First: A charge of fresh combustible mixture, or air, is positively delivered to each power cylinder in the direction to produce the most efficient scavenging effect therein, by elimination of products of combustion after each power stroke. 70

Second: The burnt gases are thus exhausted and the fresh charge of combustible mixture admitted with the least possible chance of mixing with each other. 75

Third: The pressure of the scavenging charge is as low as possible; not being admitted until the exhaust pressure is practically equal to that of the atmosphere. 80

Fourth: The exhaust valves are closed a trifle later than the beginning of the admission of the scavenging charge; thus insuring perfect filling of the power chambers. 85

Fifth: The operation of the valves is positively effected in proper time; thus avoiding the irregularity of operation, which is incident to the operation of valves with springs. 90

Sixth: All passages are so short and direct as to reduce throttling effect to the minimum. 90

Seventh: The construction and arrangement is less complicated than prior engines. 95

Eighth: The means for holding the valves and their appurtenances in operative position renders them more easily accessible for primary assembling and subsequent repairs than in such prior engines. 100

Ninth: The inside of each piston is entirely exposed to the cooling effect of the air in the crank case. 105

Tenth: No stuffing box and extra cross head is required.

Eleventh: The parts of the valves at the hottest part of the engine, to wit, the region adjoining the spark plugs, are cooled upon both outside and inside. 110

Twelfth: The engine above described, with reference to Figs. I to VII inclusive may be used as an oil engine, pumping air instead of combustible mixture; in which case the oil must be injected in vaporous form toward the end of each outer stroke of said pistons 42. However, such use does not involve any change in the construction and arrangement shown in said figures. 115

However, the advantages above enumerated are not restricted to the specific design of my invention shown in Figs. I to VII inclusive. For instance, in Figs. VIII to XI inclusive I have shown a modified form of my invention including four cylinders, arranged in two pairs, so that while two cylinders are operating with air, the other two are operating with combustible mixtures. 120

Referring to Figs. VIII to XI inclusive; the cylinder casing 81 is similar to the casing 1 above described, in its general ar- 130

angement, in that the cylinders, of which there are four, are lined with stationary sleeves 82 which are larger at their inner ends, than at their outer ends, to form charging chambers 83 and power chambers 84; like the chambers 46 and 28 above described. However, the crank shaft 86 has cranks 87 arranged in pairs, projecting radially oppositely so that the pistons 89 in the opposite end cylinders in said casing 81 are thrust outwardly, while the pistons in the inner adjoining cylinders in said casing 81 are drawn inwardly, and vice versa.

Each of said stationary sleeves 82 has a rotary valve 91 fitted to turn therein like the valves 17 above described and similarly rotated by connection with said crank shaft 86.

As shown in Figs. IX and X, said casing 81 has oppositely counterpart admission ports 92 and 93 leading to respective admission or receiving chambers 94 which have ports 95 in the conical portions of said sleeves 82, opening inwardly and adapted to register with ports 96 in said sleeves 91, leading into said charging chambers 83. The chambers 97 extend oppositely to said chambers 94, beyond the transverse partitions 98 upon respectively opposite sides of the longitudinal partitions 99 in said casing 81 which partitions separate said chambers from each other. Said chambers 97 are in communication with ports 100 which, when registered with ports 101 in said valves 91, lead into said power or combustion chambers 84; so that said cylinders and pistons are operative in pairs to alternately pump air and fuel.

The outer portion of said casing 81 forms exhaust chambers 102 having respective outlets 103, and inclosing circular series of ports 104 respectively encircling each of said sleeves 82 and in registry with ports 106 in said sleeves. Said ports 104 and 106 register with corresponding ports 107 in the cylinder heads 108 which are respectively rigidly connected with said casing 81 and extend within said valves 91; which latter have ports 109 adapted to register with said exhaust ports, in the manner above described with reference to the construction and arrangement shown in Figs. I to VII inclusive. Spark plugs are indicated at 110.

Fig. XI shows the steps in the operation of the engine last above described with the crank turning in the direction of the arrow in said figure, 114 indicating the point at which the exhaust opens, and 115 the point of closing the same. The ports for scavenging open at the point 116 and close at the point 117 and the combustible mixture is admitted at the point 118.

Referring to Fig. VIII; it is to be understood that the left hand pair of cylinders may be used to deliver the scavenging air

to all four cylinders, and that the right hand pair of cylinders may be used to deliver the combustible mixture to all four cylinders; the air and combustible mixture being separately admitted to the casing 81 through the respective admission ports 92 and 93 which, as shown in Fig. IX, are on opposite sides of said casing.

Therefore, it is to be understood that I do not desire to limit myself to the precise details of arrangement herein set forth, as it is obvious that various modifications may be made therein without departing from the essential features of my invention, as defined in the appended claims.

I claim:

1. In an internal combustion engine; the combination with an outer cylinder casing, formed of a single casting, with a plurality of cylindrical chambers therein, each having water jacket recesses in its inner wall, said recesses being primarily open inwardly; said cylinder casing having sectoral stepped flanges in concentric relation with the respective axes of said cylindrical chambers therein; of stationary cylindrical sleeves each forming the inner walls of said jacket recesses, and two cylindrical chambers of different diameters; each of said sleeves having respective circular series of ports in three zones; rotary tubular valves each having two portions of different diameters mounted to turn in said sleeves, and having three circular series of ports arranged to vary the effective area of said ports in said sleeves; a crank shaft casing, rigidly connected with said cylinder casing; a crank shaft journaled in said shaft casing; the larger diameters of said sleeves and valves being nearer the crank shaft than the smaller diameters thereof; pistons mounted to reciprocate in said sleeve valves, and having portions of two diameters respectively fitted to slide in the two diameters of said valves; the larger diameters of said pistons cooperating with the larger diameters of said valves to form pump chambers between them, arranged to alternately intake and charge fluid into the combustion and power chambers, which are in the smaller diametrical portions of said valves; connecting rods respectively connecting said pistons with the cranks of said shaft; each of said valves having, at the larger end thereof, an external series of gear teeth; the gear teeth of the respective valves being intermeshed with each other; a gear pinion meshed with the teeth of one of said valves; a countershaft, extending transversely to said shafts, and carrying said pinion; a bevel gear upon the opposite end of said countershaft; a bevel gear upon said crank shaft in mesh with the bevel gear on said countershaft; and means normally maintaining said valves in assembled position in said cylinder casing, includ-

120
125
130

ing sectoral abutment bearing blocks seated upon said sectoral stepped flanges in said cylinder casing.

2. In an internal combustion engine; the combination with an outer cylinder casing, with a plurality of cylindrical chambers therein, each having water jacket recesses in its inner wall, said recesses being primarily open inwardly; said cylinder casing having sectoral flanges in concentric relation with the respective axes of said cylindrical chambers therein; of stationary cylindrical sleeves each forming the inner walls of said jacket recesses, and two cylindrical chambers of different diameters; each of said sleeves having respective circular series of ports in three zones; rotary tubular valves each having two portions of different diameters mounted to turn in said sleeves, and having three circular series of ports arranged to vary the effective area of said ports in said sleeves; a crank shaft casing, connected with said cylinder casing; a crank shaft journaled in said shaft casing; the larger diameters of said sleeves and valves being nearer the crank shaft than the smaller diameters thereof; pistons mounted to reciprocate in said valves, and having portions of two diameters respectively fitted to slide in the two diameters of said valves; the larger diameters of said pistons cooperating with the larger diameters of said valves to form pump chambers between them, arranged to alternately intake and charge fluid into the combustion, power, chambers which are in the smaller diametrical portions of said valves; connecting rods respectively connecting said pistons with the cranks of said shaft; each of said valves having, at the larger end thereof, an external series of gear teeth; the gear teeth of the respective valves being intermeshed with each other; gear means operatively connecting said valve gears with said crank shaft; and means normally maintaining said valves in assembled position in said cylinder casing, including sectoral abutment bearing blocks seated upon said sectoral flanges in said cylinder casing.

3. In an internal combustion engine; the combination with an outer cylinder casing, with a plurality of cylindrical chambers therein, each having water jacket recesses in its inner wall, said recesses being primarily open inwardly; said cylinder casing having sectoral flanges in concentric relation with the respective axes of said cylindrical chambers therein; of stationary cylindrical sleeves each forming the inner walls of said jacket recesses, and two cylindrical chambers of different diameters; each of said sleeves hav-

ing respective circular series of ports; rotary tubular valves each having two portions of different diameters mounted to turn in said sleeves, and having circular series of ports arranged to vary the effective area of said ports in said sleeves; a crank shaft casing; a crank shaft journaled in said shaft casing; the larger diameters of said sleeves and valves being nearer the crank shaft than the smaller diameters thereof; pistons mounted to reciprocate in said valves, and having portions of two diameters respectively fitted to slide in the two diameters of said valves; the larger diameters of said pistons cooperating with the larger diameters of said valves to form pump chambers between them, arranged to alternately intake and charge fluid into the combustion, power, chambers which are in the smaller diametrical portions of said valves; connecting rods respectively connecting said pistons with the cranks of said shaft; each of said valves having, at the larger end thereof, an external series of gear teeth; the gear teeth of the respective valves being intermeshed with each other; gear means operatively connecting said valve gears with said crank shaft; and means normally maintaining said valves in assembled position in said cylinder casing, including sectoral abutment bearing blocks seated upon said sectoral flanges in said cylinder casing.

4. In an internal combustion engine; the combination with an outer cylinder casing, with a plurality of cylindrical chambers therein; said cylinder casing having sectoral flanges in concentric relation with the respective axes of said cylindrical chambers therein; of stationary cylindrical sleeves fitted in said casing chambers, and each forming two cylindrical chambers of different diameters; each of said sleeves having respective circular series of ports in three zones; one of said zones being conical; rotary tubular valves each having two portions of different diameters mounted to turn in said sleeves, and having circular series of ports arranged in three zones, fitted to said sleeve zones and arranged to vary the effective area of said sleeve ports; a crank shaft casing, rigidly connected with said cylinder casing; a crank shaft journaled in said shaft casing; the larger diameters of said sleeves and valves being nearer the crank shaft than the smaller diameters thereof; pistons mounted to reciprocate in said valves, and having portions of two diameters respectively fitted to slide in the two diameters of said valves; the larger diameters of said pistons cooperating with the larger diameters of said valves to form pump chambers between them, arranged to alternately intake and charge fluid into the combustion, power, chambers which are in the smaller diametrical portions of said valves; means operatively connecting

- 6 said pistons with the cranks of said shaft; each of said valves having an external series of gear teeth; the gear teeth of the respective valves being intermeshed with each other; means operatively connecting said valve gears with said crank shaft; and means normally maintaining said valves in assembled position in said cylinder casing, including sectoral abutment bearing blocks seated upon said sectoral stepped flanges in said cylinder casing.
5. In an internal combustion engine; the combination with an outer cylinder casing, with a plurality of cylindrical chambers therein; said cylinder casing having sectoral flanges in concentric relation with the respective axes of said cylindrical chambers therein; of stationary cylindrical sleeves in said casing chambers forming two cylindrical chambers of different diameters; each of said sleeves having respective circular series of ports; rotary tubular valves each having two portions of different diameters mounted to turn in said sleeves, and having circular series of ports arranged to vary the effective area of said ports in said sleeves; a crank shaft casing, connected with said cylinder casing; a crank shaft journaled in said shaft casing; pistons mounted to reciprocate in said valves, and having portions of two diameters respectively fitted to slide in the two diameters of said valves; the larger diameter of said piston cooperating with the larger diameter of said valve to form a pump chamber between them, arranged to alternately intake and charge fluid into the combustion, power, chamber which is in the smaller diametrical portion of said valve; means operatively connecting said piston with said crank shaft; and means normally maintaining said valve in assembled position in said cylinder casing, including sectoral abutment bearing blocks seated upon said sectoral flanges in said cylinder casing.
- 10 5. In an internal combustion engine; the combination with an outer cylinder casing, with a cylindrical chamber therein; of a stationary cylindrical sleeve fitted in said casing chamber and forming two cylindrical chambers of two diameters in co-axial relation; a rotary cylindrical valve, fitted in said sleeve and forming two piston chambers of different diameters in co-axial relation; a piston having two portions of different diameters mounted to reciprocate in said valve, arranged to form a combustion chamber between the smaller diameter of said piston, and the smaller diameter of said valve, and to form a pump chamber between the larger diameter of said piston, and the larger diameter of said valve; said sleeve and valve having circular series of ports arranged to register with each other and to vary their effective area; and means arranged to continuously rotate said valve while reciprocating said piston; whereby said ports in said valve register with ports in said sleeve twice in each revolution, but only once while said ports are uncovered by said piston; and automatically effect a "scavenging" operation whereby the products of combustion in said combustion chambers are discharged therefrom by fluid under pressure from said pump chamber during the operation of said structure as a two cycle engine.
- 15 6. In an internal combustion engine; the combination with an outer cylinder casing, with a cylindrical chamber therein, having a water jacket recess in its inner wall, said recess being primarily open inwardly; said cylinder casing having sectoral flanges in concentric relation with the axis of said cylindrical chamber therein; of a stationary cylindrical sleeve forming the inner walls of said jacket recesses, and two cylindrical chambers of different diameters; said sleeve having circular series of ports in three zones; a rotary tubular valve having two portions of different diameters mounted to turn in said sleeve, and having three circular series of ports arranged to register with and vary the effective area of said ports in said sleeves; a crank shaft casing, connected with said cylinder casing; a crank shaft journaled in said shaft casing; a piston mounted to reciprocate in said valve, and
- 20 7. In an internal combustion engine; the combination with an outer cylinder casing, with a cylindrical chamber therein; of a stationary cylindrical sleeve fitted in said casing chamber and forming two cylindrical chambers of two diameters in co-axial relation; a rotary cylindrical valve, fitted in said sleeve and forming two piston chambers of different diameters in co-axial relation; a piston having two portions of different diameters mounted to reciprocate in said valve, arranged to form a combustion chamber between the smaller diameter of said piston, and the smaller diameter of said valve, and to form a pump chamber between the larger diameter of said piston, and the larger diameter of said valve; said sleeve and valve having circular series of ports arranged to register with each other and to vary their effective area; and means arranged to continuously rotate said valve while reciprocating said piston; whereby said ports in said valve register with ports in said sleeve twice in each revolution, but only once while said ports are uncovered by said piston; and automatically effect a "scavenging" operation whereby the products of combustion in said combustion chambers are discharged therefrom by fluid under pressure from said pump chamber during the operation of said structure as a two cycle engine.
- 25 8. In an internal combustion engine; the combination with an outer cylinder casing, with a cylindrical chamber therein, having a water jacket recess in its inner wall, said recess being primarily open inwardly; said cylinder casing having a sectoral flange in concentric relation with the axis of said chamber; of a stationary cylindrical sleeve forming the inner wall of said jacket recess and two cylindrical chambers of different diameters; and means normally maintaining said sleeve in assembled position in said cylinder casing and preventing axial movement thereof, including a sectoral abutment bearing block seated upon said sectoral flanges in said cylinder casing.
- 30 9. In an internal combustion engine; the combination with four cylinders; of pistons respectively mounted to reciprocate in said

cylinders; a crank shaft having four cranks; means operatively connecting said cranks with said pistons; and valve means in co-
axial relation with said pistons and opera-
5 tively connected with said crank shaft, con-
structed and arranged to effect a two cycle
operation of the engine; means arranged to
prevent axial movement of said valve means;

said cylinders and pistons being arranged in
pairs operative to pump air and fuel alter-
nately; one pair pumping air while the other
pair is pumping gas.

In testimony whereof, I have hereunto
signed my name at Philadelphia, Pennsyl-
vania, this 22nd day of September, 1924.

MARTIN PLASS.
